F. BUCK

FOLDING RULE

Filed Nov. 7, 1921

Inventor
Fred Buck

By Whittimore Hulbert Whittimore
+ Belknap Attorneys

UNITED STATES PATENT OFFICE.

FRED BUCK, OF SAGINAW, MICHIGAN, ASSIGNOR TO THE LUFKIN RULE COMPANY, OF SAGINAW, MICHIGAN, A CORPORATION OF MICHIGAN.

FOLDING RULE.

Application filed November 7, 1921. Serial No. 513,247.

To all whom it may concern:

Be it known that I, FRED BUCK, a citizen of the United States of America, residing at Saginaw, in the county of Saginaw and 5 State of Michigan, have invented certain new and useful Improvements in Folding Rules, of which the following is a specification, reference being had therein to the accompanying drawings.

10 The invention relates to folding rules and refers particularly to that type adapted for use in making inside measurements and comprising a series of pivotally connected sections with an extension member longitudinally slidably secured to an end section. The invention has for its object the provision of a folding rule in which the total inside measurement secured by the sections in extended position and the extension member can be directly obtained without the necessity of adding the measurement of the sections in extended position to the measurement of the extension member. More in detail, the object of the invention is to provide 15 a folding rule comprising an end section to which the extension member is longitudinally slidably secured, and a plurality of additional sections, the last-mentioned sections each having a base indication exposed when the respective section is rotated into extended position and indicating the total length of the sections in extended position, the end section having a pair of scales cooperating with the extension member and with the base indications on the alternate additional sections and provided with digit indications in continuation of the base indications, whereby the total inside measurement secured by the sections 20 in extended position and the gage member may be directly secured. With these as well as other objects in view, the invention resides in the novel features of construction as more fully hereinafter set forth.

25

45 In the drawings:

Figure 1 is a front elevation of a folding rule embodying my invention with certain of the sections in extended position;

Figure 2 is a similar view with a different number of sections in extended position;

Figure 3 is a front elevation of a modified construction with certain of the sections in extended position.

The folding rule comprises a series of pivotally connected sections which are 55 adapted to be rotated from folded position into extended position and which are automatically held in this extended position by snap engagement of the pivoted ends of the sections. 1 is an end section which is 60 provided with the pair of longitudinally extending scales 2 and 3 and which has the inverted T-slot 4 extending longitudinally thereof and between the scales for slidable engagement by the extension member 5, the 65 outer face of which is substantially flush with the corresponding face of the end section. The extension member is slidable in opposite directions and is provided with suitable distance indicating means 6 and 7 70 for cooperating with the scales 2 and 3. As shown in Figures 1 and 2, the indicating means comprise fingers secured to the extension member and extending beyond its outer face so that they also may be used 75 in manually adjusting the extension member. 8, 9 and 10 etc. are a plurality of additional sections which are of such a length that when rotated into extended position each will increase the total length of the 80 rule by the same distance. As shown in Figures 1 and 2, the length of the increments is 5 inches. The additional sections 8, 9, 10 etc. are adapted to be successively 85 rotated relative to the end section 1 into extended position and are provided on their faces corresponding to the face of the end section 1 upon which the scales 2 and 3 are located with the base indications 11 which are exposed when their respective sections 90 are rotated into extended positions and which indicate the total lengths of the extended sections of the rule including the length of the end section. Thus as shown in Figures 1 and 2, the section 8 has the 95 base indication "10" which indicates that the total length of the section 8 and end section 1 is 10 inches when in extended position. Also the section 9 has the base indication "15" which indicates that the total 100 length of the sections 8, 9 and end section 1 is 15 inches when in extended position. Thus it is seen that the base indication stating the total length of the sections in extended position is immediately adjacent 105 to the end section 1.

In order to simplify the reading of the inside measurement which might be the total of a certain number of sections in extended position plus a certain distance through which the extension member is longitudinally moved, the scales 2 and 3 are provided with digit indications beginning at opposite ends of the end section and so arranged that they are in continuation of the base indications upon the alternate additional sections 8, 9, 10, etc., of the rule. In other words, the scales are arranged so that the measurement indicated thereon by either the fingers 6 or 7 is substituted in lieu of the second figure of the base indication on the extended section immediately adjacent to the end section. As an example, assuming that the parts are in the position shown in Figure 1 in which the base indication on the exposed section 9 immediately adjacent to the end section 1 is "15" and that the finger 6 indicates the figure 8 upon the scale 2, the figure 8 would be substituted in lieu of the figure 5 and the inside measurement given by this rule would be 18 inches. On the other hand assuming that the parts are in position shown in Figure 2 where the base indication "20" is exposed upon the section 10 immediately adjacent to the end section 1 and the indicating finger 7 points to the figure 2 upon the scale 3, the total inside measurement is 22 inches.

It will be seen that with the above arrangement, the end section 1 is reversed relative to the exposed sections each time an additional section is rotated from folded position into extended position so that as a consequence, the scales are adapted for use with alternate sections of the rule.

In the modification shown in Figure 3, the folding rule is of larger size and comprises sections which successively increase the total length of the rule by 10 inch increments, the first section 12 having the base indication "20" indicating the total length of the first section and end section 13 to be 20 inches. The second section 14 has the base indication "30" and the successive sections have base indications which successively increase by 10 inches. In this case, the scales 15 and 16 upon the end section 13 are provided with the same digit indications although they begin at opposite ends of the end section, owing to the fact that the end section is alternately reversed with respect to the exposed sections as additional sections are rotated from folded into exposed position. Furthermore, the extension member 17 has the indicating marks 18 and 19 for cooperating with the scales 15 and 16 and has the small knobs 20 for facilitating in manually sliding the extension member.

The opposite faces of the pivotally connected sections of the folding rule are pro-

vided with suitable graduations as in the usual construction so that the rule may be used for outside measurements as well.

From the above description, it will be readily seen that I have provided a simple construction of folding rule which is designed particularly for use in making inside measurements and in which means is provided for directly indicating the length of the inside measurements without the necessity of adding two separately indicated lengths thereby eliminating any liability on the part of the man using the rule of making a mental mis-calculation.

While the unit of length mentioned above is inches, it is obvious that the unit might be feet and inches or that the metric system might be employed.

What I claim as my invention is:

1. In a folding rule, a plurality of pivotally connected sections, one of said sections having a pair of spaced longitudinal scales, another section having a base indication thereon, an extension member extending longitudinally of and slidably secured to said last-mentioned section between said scales and provided with means adapted to designate a figure of said scales for cooperation with said base indication.

2. In a folding rule a series of pivotally connected sections, including an end section and a plurality of sections adapted to be successively rotated relatively to said end section into extended position, said end section having a pair of longitudinally extending scales, the other of said sections having base indications thereon, an extension member extending longitudinally of and slidably secured to said end section to be movable in opposite directions between said scales, said gage member being provided with means adapted to designate a figure of said scales for cooperation with said base indications.

3. In a folding rule, the combination with an end section provided with a pair of longitudinally extending scales beginning at opposite ends and a plurality of pivotally connected sections adapted to be successively rotated relative to said end section into extended position, of an extension member extending longitudinally between said scales and slidably secured to said end section to be movable in opposite directions, said gage member having distance indicating means for cooperating with each of said scales.

4. In a folding rule, the combination with a series of pivotally connected sections, including an end section and a plurality of additional sections adapted to be successively rotated relative to said end section into extended position, each of said additional sections having a base indication thereon exposed when the respective section is rotated into extended position and indicating the total length of the sections in extended po-

- sition, and said end section having a pair of longitudinally extending scales each cooperating with the base indications on the alternate additional sections and provided 5 with digit indications in continuation of the base indications for giving the direct readings, of an extension member extending longitudinally of and slidably secured to said end section to be movable in opposite 10 directions, said extension member being provided with distance indicating means for cooperating with said scales.
5. In a rule, the combination with a series of pivotally connected sections, of a 15 scale member pivotally connected to one of said sections, an extension member cooperating with said scale member, each of said pivotally connected sections having a base indication, said scale member having a scale 20 provided with digit indications for cooperation with the respective base indications upon said pivotally connected sections, and said extension member having distance indicating means cooperating with said scale.
- 25 6. In a folding rule, a plurality of pivotally connected sections, one end section having a longitudinal scale, another section having a base indication thereon, an extension member extending longitudinally of 30 and slidably secured to said end section, and

a finger carried by said end section adapted to designate a digit of said scale for cooperation with said base indication.

7. In a folding rule, the combination with a plurality of pivotally connected sections, 35 an end section having a longitudinal scale, of an extension member extending longitudinally of and slidably secured to said end section, a finger carried by said member cooperating with said scale to indicate the distance the outer end of said member is extended from said end section, the other of said pivotally connected sections having base indications denoting the length of the 40 respective sections, the distance indicated by said finger being substituted in lieu of the second figure of the base indication disposed upon the section adjacent to said end section to secure the desired measurement.

8. In a folding rule, the combination with 50 a plurality of pivotally connected sections, an end section having a longitudinal scale, of an extension member slidably secured to said end section, the other of said sections having base indications, and means carried 55 by said extension member for cooperating with said scale and said base indications.

In testimony whereof I affix my signature.

FRED BUCK.
